OIL FILTER WRENCH

Frank H. Liljemark, Minneapolis, Minn., assignor to Electro Specialty Manufacturing Co., Minneapolis, Minn., a corporation of Minnesota

Filed Dec. 28, 1965, Ser. No. 351

Term of patent 14 years

(Cl. D54—16)

FIG 1

FIG 2

FIG 3

FIG 4

FIG 5

FIG. 1 is a front elevational view of an oil filter wrench embodying my design;

FIG. 2 is a side elevational view thereof;

FIG. 3 is an opposite side elevational view thereof;

FIG. 4 is an end elevational view thereof;

FIG. 5 is an opposite end elevational view thereof.

A rear elevational view thereof is substantially a mirror image of that shown in FIG. 1.

I claim:

The ornamental design for an oil filter wrench, as shown and described.
